UNITED STATES PATENT OFFICE.

HENRY J. STUART, OF DERBY, CONNECTICUT, ASSIGNOR TO ROBERT N. BASSETT COMPANY, INCORPORATED, OF SHELTON, CONNECTICUT, A CORPORATION OF CONNECTICUT.

BUTTON-CLASP.

1,283,955.

Patented Nov. 5, 1918.

Application filed August 15, 1916. Serial No. 114,964.

To all whom it may concern:

Be it known that I, HENRY J. STUART, a citizen of the United States, residing at Derby, in the county of New Haven and State of Connecticut, have invented a certain new and useful Improvement in Button-Clasps, of which the following is a specification.

My invention relates to button clasps for hose supporters and like articles, but more particularly to that class of the same wherein fabric or other non-elastic material is disposed over the front face of the base of the button, and its principal object is to provide a device of this character to which the fabric material is held against the base by the underside of an elastic flange or collet.

In the drawings:

Figure 1 is a front view of the clasp; Fig. 2, a central, longitudinal section but showing the loop swung forwardly out of engagement with the button;

Fig. 3, a sectional view of the tape and stud during the process of assembling; Figs. 4, 5 and 6, detail views of the separate parts of the button;

Fig. 7, a sectional view of a modification, and

Figs. 8 and 9, detail views of a further modification.

The button clasp generally consists of an attaching loop A, a button loop B and a button tab or tape C which carries a button D at its lower extremity. The button loop B, which is connected to the lower side of the attaching loop A by a lip E projecting from the upper side thereof, is provided with a bridge F and has the sides of its lower extremity contracted to engage the shank of the button D. With the exception of the button D and the manner of attaching the same to the tape C the device thus far described is one of the common forms of button clasps well known in the art and is disclosed herein merely to show how my invention is applied. The button D consists of a circular, or substantially circular, metal base 2. Projecting outwardly and riveted to the base 2 is a wire stud 3. The stud 3 is headed to form a convex head 4. The elastic rubber cap or collet 6 is shaped to form a head 7 and a neck or shank 8. The collet 6 is provided with a central aperture 9 having an inside cylindrical wall 10 flared outwardly at its upper extremity. The diameter of the wall 10 is less than that of the head 4 and preferably less than that of the shank of the stud 3. The circular flange 11, which is of slightly greater diameter than the base 2, is provided with a central aperture 12 and has its top side countersunk to form a seat 13 for the reception of the lower end of the neck 8 of the collet. The button tape C has one of its extremities *a* punched to form adjacent apertures 14, 15 and its other extremity *b* also punched to form an aperture 16. In assembling the parts the extremity *b* of the tape is slipped over the head 4 of the stud, or to be more exact the head 4 is slipped through the aperture 16 of the tape. The tape is then passed around in back of the base 2 and the extremity *a* threaded forwardly through the attaching loop A and rearwardly over the bridge F. The extremity *a* is then folded on itself between the adjacent apertures 14 and 15 so that the latter will register when the two layers of the fold are brought together. The folded extremity *a* is then slipped over the head 4 of the stud, the latter passing through the registering apertures 14 and 15, as shown in Fig. 3. The elastic flange 11 is then slipped over the head of the stud and pressed down upon the tape, then the elastic collet 6 is pressed over the head of the stud, which passes through the aperture 9 therein, filling the space between the underside of the head of the stud and the front face of the flange and causes the latter to coact with the base plate 2 to prevent the folded extremities of the tape from displacement or from slipping out of alinement. The tape being wider than the base covers and conceals the latter, thereby obviating any disadvantages incident to the exposure of a metal part. The elastic flange 11 being wider than the metal base 2 overlaps the edges of the latter, thereby presenting a soft edge around the periphery of the base. This prevents the metallic edge of the base 100

from pressing against the garments or body of the wearer. Since the flange is nearly of the same width as the tape it keeps the latter uniformly spread against the front face 5 of the base and prevents the tape from slipping out of alinement. The neck 8, together with the underside 17 of the collet and the upper side 18 of the flange co-act with the upper and lower faces and the inner edge 10 of the loop B, which is shown made of sheet metal, to grip the stocking or other garment. It should be observed that the end edges of 15 the tape are embraced between the layers of, and concealed inside the folds, thereby preventing these ends from raveling and also 20 from presenting rough edges on the exterior surface of the tape. Since the extremities of the tape are gripped securely between the flange and base plate no stitching or 25 sewing is required in assembling the parts since the assembled parts of the button may be the sole means for fastening the ends of the tape.

The secured extremity of the tape may be 25 fastened in other ways than that above described, a particular instance being shown in Fig. 7 in which the tape C' is folded to form three layers 19, 20 and 21 provided with registering apertures through which the stud 22 30 is passed. In this modification the flange 23 is made integral with the neck 24 of the collet 25 and of substantially the same diameter as the metal base 26. The upper extremity of the tape is fastened to the clasp 35 in any desired manner.

Referring to the modification shown in Figs. 8 and 9, the extremities c and d of the tape C² are both connected to the back ply e by stitches f, f in order to prevent the back 40 ply from swinging away from the rear side of the button plate 27. The elastic flange 28 and the base plate 27 are both made rectangular, the flange being slightly wider than the base. The collet 29 covers the head 45 30 of the stud 31 so that the latter does not pass entirely through the collet.

I have herein referred to the flange and collet as being made of elastic rubber but my invention is intended to comprehend flanges 50 and collets made of other elastic or springy material. It should be observed that when both the flange and collet are made of elastic material, either integral or in separate parts, they form a cushion which can be readily 55 sprung over the head of the stud and down upon the fabric, thereby enabling the button to be assembled by hand. It should also be observed that the flange holds down the corners of the tape thereby preventing them 60 from catching in the lower extremity of the loop when the latter is engaging the button.

While the preferred forms of my invention are embodied in the devices above described, yet the same are susceptible to such

modification as may fairly come within the 65 scope of the appended claims.

Having now described my invention what I claim and desire to protect by Letters Patent is:

1. In a button clasp an apertured fabric 70 and a button, the said button comprising a base provided with a projecting stud which passes through said fabric, a flange having the same contour as the base surrounding said stud in front of said fabric and an elastic collet surrounding said stud in front of 75 said flange to hold the latter against the fabric.

2. In a button clasp an apertured fabric 80 and a button, the said button comprising a base plate provided with a headed stud which passes through said fabric and a flange having a collet mounted thereon surrounding said stud in front of said fabric, the said flange and collet being made of 85 elastic material and filling the space between the front of the fabric and the head of the stud.

3. In a button clasp a button base plate provided with a projecting stud, an apertured 90 fabric disposed over the front side of said base plate, an elastic flange surrounding said stud in front of said fabric, the said flange being wider than said base plate.

4. In a button clasp a base plate provided 95 with a projecting headed stud, the said base plate having its front side covered with fabric material through which said stud extends and an elastic cushion surrounding 100 said stud in front of said fabric material and containing a passage of less diameter than the head of the stud, the said cushion being provided with an outwardly projecting flange at its inner extremity which overlaps the edges of said base plate.

5. In a button clasp a base plate having 105 its front side covered with fabric material and an elastic cushion mounted thereon in front of said fabric material, the said cushion overlapping the edges of said base 110 plate and having the same contour as said base plate.

6. In a button clasp a base plate having its front side covered with fabric material, an elastic cushion mounted thereon in front of 115 said fabric material, the said cushion overlapping said base plate and means for causing said cushion to co-act with said base plate to grip the fabric material.

7. In a button clasp a base plate provided 120 with a projecting headed stud, the said base plate having its front side covered with fabric material through which said stud extends and an elastic cushion surrounding 125 said stud in front of said fabric material and containing a passage of less diameter than the head of the stud, the said cushion filling the space between the front of the

fabric material and the under side of the head of the stud and being provided with an outwardly projecting flange at its inner extremity which overlaps the edges of said base plate.

8. A button for a button clasp comprising a base, an elastic cushion attached to said

base, and a collet mounted on said cushion and also attached to said base, the said cushion being provided with a seat for positioning the inner extremity of said collet. 10

In testimony whereof I have hereunto set my hand this 28th day of July, 1916.

HENRY J. STUART.
